Application August 10, 1934, Serial No. 739,206

5 Claims. (CL. 68—38)

Our present invention relates generally to cleaning apparatus, and has particular reference to a type of apparatus intended for the so-called "dry cleaning" of garments and the like.

One of the main objects of our invention is to provide a unitary and compact installation which is intended to employ and reemploy a fixed quantity of cleaning fluid, except for such minor additional amounts as may be required from time to time to make up for losses.

One of the features of our invention lies in providing an apparatus in which a circulating system for the cleaning fluid is adapted to subject the fluid continuously to a clarifying and a filtering action. By the term "clarifying" we refer to the type of treatment whereby the cleaning fluid is subjected to certain chemicals or equivalent materials; and by the term "filtering" we refer to the type of treatment whereby the fluid is caused to pass through a porous material, such as a bag, having a mechanical filtering action.

In accordance with our invention, a circulating system is associated with a cleaning drum and an extracting chamber in a manner whereby selected quantities of filtered and clarified cleaning fluid may be introduced, from time to time, into the cleaning drum and may be withdrawn therefrom and resubjected to the continuous clarifying and filtering treatment.

Another general object of our invention is to provide a device which may be efficiently and conveniently manipulated and attended by a single operator, enabling him with facility to subject garments or the like to a cleaning operation, one or more rinsing procedures, and finally to an extracting or drying action.

Among the features of our invention leading to the achievement of the foregoing general objectives is an arrangement whereby a rotatable cleaning drum is mounted above an extracting chamber, and the latter is in turn mounted above the filtering device of the circulating system. The extracting chamber is provided with a top opening, and the cleaning drum is provided with a feeding aperture which may be brought into a position directly above said opening, whereby garments or articles from the cleaning drum may be caused to fall by gravity into the extracting chamber after the cleaning and/or rinsing operations have been completed. Within the extracting chamber is an extracting basket positioned to receive such articles.

55 By mounting the filtering device beneath the

extracting chamber, and by providing a suitable conduit communicating directly from the chamber to the filtering device, it is possible to gain access to the filtering device for cleaning purposes or the like by temporarily feeding all of the cleaning fluid from the circulating system into the cleaning drum and extracting chamber, and redirecting it ultimately, by gravity, back into the circulating system.

Another feature of our invention lies in providing a filtering device in the form of a tank in which a filter bag or, preferably, a plurality of such bags, is arranged, means being provided for introducing unclean fluid into the interior of the bag or bags and forcing it to pass outwardly through the bag or bags, thereby subjecting it to a mechanical filtering action.

Another feature lies in a unique arrangement of clarifying compartment, through which the cleaning fluid is caused to pass and in which it is mixed with certain suitable chemicals, the fluid and the chemicals then passing together into the filter bags. A characterizing feature of our invention lies in providing the clarifying compartment with a stiletto-like perforated outlet conduit in the bottom wall, whereby a measured charge of the clarifying material may be accommodated within a container which fits snugly into the compartment and whereby the container may be inserted bodily into the compartment and impaled over the outlet conduit.

Other features of our invention lie in the general construction and arrangement of the several parts, whereby a unitary and highly efficient apparatus results, having unique capabilities from the standpoint of efficiently subjecting articles, in considerable quantities, and in an economical manner, to the several processes involved in the so-called dry cleaning of garments.

We achieve the foregoing objects, and such other objects as may hereinafter appear or be pointed out, in the manner illustratively exemplified in the accompanying drawings, wherein—

Figure 1 is a front elevational view of a complete apparatus embodying the features of the present invention;

Figure 2 is a side view of Figure 1;

Figure 3 is a diagrammatic view showing the relationship of the various parts and the elements of the circulating system;

Figure 4 is a cross-sectional view taken through the cleaning drum and illustrating features of its construction;

view showing the manner in which garments are introduced from the cleaning drum to the extracting basket;

Figure 6 is a side view of one of the filter bags, 5 this view being taken substantially along the line 6—6 of Figure 1;

Figure 7 is a cross-sectional view, on an enlarged scale, through the clarifying compartment; and

10 Figure 8 is a cross-sectional view taken substantially along the line 8—8 of Figure 1, showing the details of a clutching arrangement.

The apparatus is assembled on a skeleton framework which consists essentially of the two 15 spaced upright frames 10 and 11, braced by the cross-pieces 12, 13, and 14. Inasmuch as the supporting framework forms no direct part of our invention (except in so far as the relative arrangement of parts is concerned), details of 20 the same in the further description of the apparatus will be omitted, although it will be understood by those skilled in the art that suitable brackets, supports, and other common structural expedients are employed wherever necessary.

25 The apparatus consists essentially of a cleaning drum, an extractor, and a fluid circulating system which clarifies and filters a fixed quantity of fluid.

30 The cleaning drum 15 is substantially cylindrical and is arranged with its axis horizontal. It is mounted for rotational movement about a horizontal axis which is eccentric with respect to the axis of the drum. Upon reference to Figures 1 and 2 it will be observed that the drum is 35 mounted between the upper ends of the supports 10 and 11, the pivot bearings being designated by the reference numeral 16.

The rotational movement of the drum is carried out by means of a motor 17 and gearing 40 mounted in the box 18. The latter gearing drives a main gear 26 which is mounted in the gear box 19 and is concentric with the axis of rotation of the drum. The transmission includes an idler gear 21 (Figure 8) which is adapted to be withdrawn 45 from the gear train, at will, by means of the control handle 20.

This clutching and declutching arrangement is diagrammatically shown in Figure 8. The idler gear 21, which is constantly in mesh with the gear 22 (driven from the train of gears in the box 18) is journaled in an arm 23 which is normally urged downwardly by means of the spring 24 and which is adapted to be cammed upwardly by the rear end 25 of the handle 20 when the latter is drawn downwardly. Thus, by drawing the handle 20 down, the driving gear 26 (in the housing 19) is brought into driven relation to the motor 17; and when the handle 20 is thrown upwardly the spring 24 withdraws the idler 21 60 from engagement with the gear 26 and thus leaves the drum free of connection with the motor.

The drum is provided with a feeding aperture 27, preferably circular, and arranged in the cylindrical side wall of the drum. A closure 28 is 65 removably held in position over the aperture by means of the clamping devices 29.

The drum is shown in its normal position in Figure 1, the feeding aperture being inclined 70 obliquely upwards, whereby it is approximately on a level with an operator's shoulders. At the bottom of the drum is a draining outlet 30 normally kept closed by means of the rotatable valve 31 but adapted to be opened by rotation of this 75 valve.

On the interior of the drum, inwardly projecting ribs 32 are provided at spaced intervals, these ribs being arranged longitudinally and being perforated. The function of these ribs is to cause a tumbling of the articles in the drum 5 during the rotation of the latter.

Mounted directly beneath the drum 15 is an extracting chamber or vat 33 provided with a top opening and a flat removable lid or cover 34. Mounted in this chamber is a rotatable extracting basket 35 (see Figure 3) which consists of a metallic shell, substantially cup-shaped, open at the top, and provided with perforations along its lower periphery. This basket is mounted for rotation about a vertical axis, and the vertical driving shaft 36 is indicated in Figure 3. Mounted on this shaft, beneath the chamber 33, is a pulley (not shown) which is belt-connected, as at 37, with a driving motor 38 (see Figure 2). The pulley on the shaft 36 is associated with a friction disc, the disc being under the influence of the compression spring 39, so that the basket 35 is never in positively driven connection with the motor 38. This permits a certain amount of slippage to take place when the rotation of the basket is initiated, and it also acts as a safeguard in the event that free rotation of the basket is impeded at any time by articles of clothing or by the hands of an operator.

The basket is very light and rotates at a great speed, since it is the function of the basket to subject the cleaned garments to a centrifugal action which results in extracting most of the cleaning fluid from them after the cleaning operation. In order to facilitate the operation of the machine, a brake is provided to enable the operator to bring the basket to a stop more quickly. This brake may consist of a brake shoe 40 mounted on the rear end of a bell crank lever 41 and adapted to be brought upwardly into engagement with a friction disc 42 carried on the lower end of the shaft 36. The movements of the brake shoe 40 are controlled by the handle 43, whereby the operator may simply grasp the handle 43 and pull it outwardly, i. e., toward him, by a slight degree, thereby stopping the rotation of the basket 35.

The fluid circulating system consists essentially of a pump 44, driven by a motor 45, a clarifying compartment 46, and a filtering device 47. 50 The circulating system is best illustrated in Figure 3, which, it will be understood, is largely diagrammatic, the actual arrangement of parts, conduits, valves, etc., being shown most clearly in Figures 1 and 2.

The pump 44 communicates, by conduits 48, 49, 50, and 51, with the top of the clarifying compartment 46. From the bottom of the latter, a conduit 52 extends to a manifold 53 to which a plurality of filter bags 54 are connected. 60 These bags, and the manifold 53, are mounted in a tank from the bottom of which conduits 55 and 56 extend back to the inlet end of the pump 44.

A closed circulating circuit is thus provided, 65 whereby a predetermined quantity of cleaning fluid is adapted to be continuously pumped successively through the clarifying compartment 46 and the filtering device 47, and thence back to the pump. This circulating system is provided with a by-pass 57 between the conduits 49 and 52. There is also provided a main flow valve 58 in the conduit 50, an indicating device 59 in the conduit 51 (with rotating vanes which indicate whether fluid is flowing or not), a pres- 75

sure gauge 60 in the conduit 51, a trap 61 in the conduit 56, a pressure-relief by-pass 62 (short-circuiting the pump), and a draining valve 63.

In order to permit a selected quantity of filtered fluid to be fed, when desired, into the cleaning drum 15, a two-way valve 64 is mounted in the conduit 49 and a conduit 65 is provided which leads axially into one end of the drum. For the purpose of permitting a draining of the fluid contents of the drum, a conduit 66 extends axially into the other end of the drum and leads downwardly to a two-way valve 67 arranged in the conduit 56. The inner end of the conduit 66 is mounted for rotation with the drum by means of suitable glands and packing; and this inner end extends along the end wall of the drum toward the bottom of the drum, as indicated in Figure 3, the term "bottom" referring to the wall in which the outlet drain 31 is arranged.

Before describing the operation of the apparatus, reference will be had to Figures 6 and 7.

In Figure 6, we have illustrated one of the filter bags 54. The bag is of material which is adapted to operate as a mechanical filtering medium. One end of it is rolled closed and held sealed by means of a removable clamp 68. The other end is adapted to be clamped (by means of a clamping arrangement 69) over a head 70, the latter communicating through a union 71 with the manifold 53. Removal and cleaning of the filter bag is accomplished by disconnecting the union 71 and removing the entire head 70 from the filter tank. Releasing the clamps 68 and 69, the bag 54 is then permitted to be withdrawn and cleaned and dried.

In Figure 7, we have illustrated the clarifying compartment 46. This compartment is provided with a cover 72 adapted to be clamped down by means of the clamping devices 73. Mounted in the bottom wall, in alignment with the outlet conduit 52, is the stiletto-like perforated inner end 74 of the conduit.

The compartment 46 is adapted to contain a measured charge of suitable clarifying and purifying material, and our invention contemplates the accommodation of such a charge (designated by the reference numeral 75) within a container 76, the container being adapted to fit snugly within the compartment 46. When a charge is to be inserted into the circulating system, the cover 72 is removed; the container 76 is impaled downwardly over the outlet conduit 74, as indicated in Figure 7; the upper cover of the container 76 is then removed and discarded; and the cover 72 of the compartment 46 is then replaced. The flow of fluid through the conduit 51 into the compartment 46 is thereby constrained to pass through the charge 75, picking up the clarifying chemical, and thence through the perforations in the stiletto-like inner end of the conduit 52. This flow is indicated by arrows in Figure 7.

The procedure in subjecting articles or garments to a dry cleaning process is as follows.

The operator first turns on the electric switch 77 which starts the motor 45 and the pump 44. The handle 78 controls the valve 64, and the handle 79 controls the valve 67, these handles being easily accessible to the operator, as shown in Figure 1. When the switch 77 is turned on, these handles are positioned to permit a flow of fluid from the pump through the clarifying compartment and the filter bags. While the flow of fluid is being established, the operator removes the cover of the cleaning drum and inserts the

articles to be cleaned. He then replaces the cover 28 and clamps it tight. A predetermined quantity of the filtered fluid is now ready to be introduced into the cleaning drum, and this is accomplished by manipulating handle 78 so that valve 64 seals conduit 50 and opens conduit 65. This causes filtered fluid to be directed upwardly through conduit 65 into the drum 15. During this operation, a vent pipe 87 permits the air in the drum to pass into the filter tank. During this feeding operation, the circulation through the filtering device 47 is maintained by virtue of the by-pass 57, thereby preventing collapse of the bags 54.

When the desired quantity of fluid is in the cleaning drum, the valve 64 is again manipulated to restore it to its initial position, and the drum is now ready to be set into rotation.

The rotation of the drum is accomplished by moving the handle 20 downwardly and by starting the motor 17. While the rotation of the drum may, if desired, be carried on in one direction, continuously, we prefer to provide an automatic reversing mechanism 80 (driven by a motor 81) which causes the drum to rotate for a period of time first in one direction and then in the opposite direction. The duration of tumbling of articles in the drum is controlled by means of the timing switch 82 which controls the duration of operation of the motor 17.

During the rotative movements of the cleaning drum, the garments are tumbled around by virtue of the eccentric mounting of the drum and by virtue of the projecting ribs 32. This tumbling subjects the articles to a thorough contact with the cleaning fluid in the drum and results in subjecting the articles to a thorough cleaning operation.

The drum is then brought to its normal position, and the handle 79 is operated to turn the valve 67 so as to close the conduit 55 and open the conduit 66. As a result, the dirty fluid is withdrawn from the drum 15 and immediately directed by the pump through the clarifying compartment 46, and into the filtering device 47. When all the fluid has been withdrawn (as will be observed at the indicator 59) the operator can, if he so desires, subject the articles to a rinsing operation by introducing a further charge of filtered fluid into the drum and repeating the foregoing operations.

Whenever the operator deems the cleaning operation within the drum 15 to be completed, he removes the cover 34 of the extracting chamber, removes the cover 28 of the drum, and swings the drum into the position of Figure 5, whereby the articles may fall by gravity from the drum into the extracting basket. The drum may be momentarily locked in this position, or in any position for that matter, by merely lowering the handle 20 and bringing the gear 26 into meshed relation to the gear 21 and the gears of the gear train from the motor 17. As long as the motor is not running, this interengagement of the gears serves as a convenient locking arrangement to hold the drum in any selected position.

When the articles have been deposited in the extracting basket, the cover 34 is replaced, and the switch 83 is thrown to start the motor 38. This sets the extracting basket into rotation and subjects the articles to a centrifugal action. During this procedure, the cleaning drum may be restored to its initial position and a new batch of articles may be fed thereto.

When the extracting operation is completed, the cover 34 is again removed from the extracting chamber, and the articles are withdrawn and hung up in a deodorizing chamber, subsequently 5 to be properly treated to a finishing operation.

Our invention is of such a character that the filter bags may be conveniently removed and cleaned at periodic intervals without the removal of any of the fixed quantity of fluid with which 10 the apparatus is supplied. To accomplish this object, we provide a special conduit 84 communicating directly between the extracting chamber 33 and the tank of the filtering device 47. A valve 85 in this conduit is first closed; the cover 15 34 of the extracting chamber is removed; the drum is brought into its normal position; and the valve 31 is opened. The handle 78 is then manipulated so as to open conduit 65; and the pump thereupon operates to withdraw all the cleaning 20 fluid from the circulating system and feed it through the conduit 65 into the drum 15. Initially, the fluid will pass freely through the drain 30 into the chamber 33. When this chamber is sufficiently filled, the valve 31 is rotated, and the 25 balance of the fluid accumulates temporarily in the drum 15. The drum 15 and the chamber 33 thus serve as temporary storage compartments for the fluid to permit ready access to the filtering tank and to the bags therein. The bags may 30 be readily reached by merely removing the cover of the filter tank, this cover being normally held closed by the clamping devices 86. When the filtering device is ready to be restored to operation, it is merely necessary to open the valve 31 and 35 the valve 85, whereby all the fluid returns by gravity into the filtering device 47.

One of the features of the embodiment herein illustrated lies in the fact that the filter tank is not of the heavy and necessarily fluid-tight nature which is ordinarily employed in dry cleaning 40 systems.

It will be understood that changes in the details, herein described and illustrated for the purpose of explaining the nature of our invention, 45 may be made by those skilled in the art without departing from the spirit and scope of the invention as expressed in the appended claims. It is, therefore, intended that these details be interpreted as illustrative, and not in a limiting sense.

Having thus described our invention, and illustrated its use, what we claim as new and desire 50 to secure by Letters Patent is—

1. In a dry cleaning apparatus, a rotatable substantially cylindrical cleaning drum mounted 55 with its axis horizontal, means for rotating the drum about an eccentric horizontal axis extending through the drum, said drum being provided with a feeding aperture in the region of the cylindrical wall which is nearer to the

axis of rotation, an extracting chamber directly beneath said drum and provided with a top opening, means for bringing said aperture into a position directly above and in registry with said chamber opening so that articles may fall by gravity from said drum into said chamber, and a rotatable extracting basket in said chamber positioned to receive said articles. 5

2. As an element of a dry cleaning apparatus, a substantially cylindrical cleaning drum adapted 10 to receive cleaning fluid and mounted with its axis horizontal, and means for rotating the drum about an eccentric horizontal axis extending through the drum.

3. In a dry cleaning apparatus, a substantially 15 cylindrical cleaning drum mounted with its axis horizontal, the drum being provided with a feeding aperture in the cylindrical wall, means for rotating the drum about an eccentric horizontal axis extending through the drum and offset from the 20 cylinder axis toward said feeding aperture, and means for locking the drum against movement in a position in which the aperture is directed downwardly. 25

4. In a dry cleaning apparatus, a substantially cylindrical cleaning drum mounted with its axis horizontal, the drum being provided with a feeding aperture in the cylindrical wall, means for rotating the drum about an eccentric horizontal axis extending through the drum and offset from the 30 cylinder axis toward said feeding aperture, means for locking the drum against movement in a position in which the aperture is directed downwardly, and an extracting chamber positioned directly beneath the drum to receive the drum contents by gravity when the drum is locked against 35 movement, as aforesaid.

5. In a dry cleaning apparatus, a cleaning drum, an extracting chamber beneath the drum, and a circulating system for cleaning fluid comprising a pump, a clarifying compartment, and a filtering device, said filtering device being mounted beneath said chamber, means for continuously pumping fluid successively through said compartment and filtering device, a drum-feeding 40 conduit for directing a selected quantity of fluid from the filtering device to said drum, a drum-draining conduit for withdrawing fluid from the drum to said compartment, an outlet in the drum adapted to be positioned over said extracting 45 chamber, and a sealable conduit from said chamber directly to said filtering device, whereby fluid from said drum may, if desired, be returned by gravity through said chamber to said filtering device independently of said drum-draining conduit. 50
